UNITED STATES PATENT OFFICE

150,946

DESIGN FOR A LAMP FIXTURE

Irving I. Gotliffe, New York, N. Y., assignor to Admiral Lamp Mfg. Corp., Chicago, Ill., a corporation of Illinois

Application April 14, 1947, Serial No. 138,351

Term of patent 7 years

(Cl. D48—20)

To all whom it may concern:

Be it known that I, Irving I. Gotliffe, a citizen of the United States and resident of New York city, in the county of New York and State of New York, have invented a new, original, and ornamental Design for a Lamp Fixture, of which the following is a specification, reference being had to the accompanying drawing, forming a part thereof.

Fig. 1 is a perspective view showing a lamp fixture embodying my new design.

Fig. 2 and Fig. 3 are elevational views of the upper and lower pedestal members respectively of the lamp fixture.

The dominant feature of the design is shown in full lines.

I claim:

The ornamental design for a lamp fixture, substantially as shown and described.

IRVING I. GOTLIFFE.
